UNITED STATES PATENT OFFICE.

JOSEPH M. RIBERT, OF NEW YORK, N. Y., ASSIGNOR TO NATIONAL NOVELTY CORPORATION, OF NEW YORK, N. Y., A CORPORATION OF NEW JERSEY.

LEMON-SQUEEZER.

SPECIFICATION forming part of Letters Patent No. 783,894, dated February 28, 1905.

Application filed October 5, 1904. Serial No. 227,262.

To all whom it may concern:

Be it known that I, JOSEPH M. RIBERT, a citizen of the United States, residing at New York, in the county of New York, State of New York, have invented certain new and useful Improvements in Lemon-Squeezers, of which the following is a description, reference being had to the accompanying drawings and to the letters of reference marked thereon.

My invention relates to what are commonly known as "lemon-squeezers"—that is, devices for expressing the juice of lemons, limes, or like fruit for use in beverages or for other purposes—and relates particularly to the class of such devices which are designed and intended for attachment to a bar-top or other support and to be operated by means of a handle.

It is the object of my invention to provide a simple, strong, and effective device for the purpose indicated capable of operation to express the juice from the lemon or other fruit by a single rotary movement of a lever all the parts of which may be formed by casting with the least possible need for dressing up or machining.

With these objects in view my invention consists in the construction and combination of elements hereinafter described, and particularly pointed out in the claims.

Referring to the drawings, Figure 1 is a side elevation of the complete device of my invention, showing the plunger depressed. Fig. 2 is a similar view, partly in section, showing the plunger raised. Fig. 3 is a plan view, on an enlarged scale, of the cup which forms the male member of the squeezing device. Fig. 4 is an elevation, on an enlarged scale, of the screw by which movement is given to the plunger, showing the parts of the screw separated; and Fig. 5 is a detail view of the upper end of the casting.

In the drawings, A is the standard, formed of a single casting having rearwardly-extending arms B C, the arm B being adapted to rest on a bar-top or table-top and the arm C being adapted to receive a screw D, between which and the arm B the bar-top or table-top (indicated at E) may be firmly gripped.

From the arm B the standard extends upward and forward, carrying at its upper end an arm F and at a lower point carrying an arm G. In the arms F and G a rod H, carrying at its lower end the plunger I, is adapted to rotate and slide. On the rod H is secured a cam-screw J. The arm G carries an antifriction-roller K, on which the cam-screw J is adapted to travel.

On the standard A below the arm C is a socket L, in which is secured the upper end of a vertical rod M. On the socket L is secured a bracket N by means of set-screw N', and on the rod M is adjustably secured a bracket O by means of set-screw O'. The bracket O is adapted to receive and sustain the serving glass or tumbler which is to receive the juice of the lemon or other fruit. The bracket N is cup-shaped, having slightly-tapered walls n and having its bottom inclined toward a central discharge-opening n'. Within the cup of the bracket N is received the male member of the squeezer, consisting of a removable cup P, having at its upper edge an exterior flange p, adapted to rest on the upper edge of the cup of the bracket N. Centrally of the cup P is an upwardly-extending projection P' having radial grooves p'. In the annular groove between the base of the projection P' and the walls of the cup are formed radial slits or openings p² of such width as to permit the juice and more or less of the finer pulp of the fruit to pass through them, but to prevent the passage of the seeds or other objectionable matter. The slits p² preferably extend upward a short distance in the walls of the cup. The depth of the cup P is such that free space is left between its bottom and the bottom of the cup of the bracket N to permit the juice and whatever of the finer pulp may pass through the slits p² to flow to the opening n'.

The cam-screw J is formed of two castings T and J² of such form that their patterns may readily be withdrawn from a sand mold. The upper casting J' has as its upper end a socket j', adapted to fit on the rod H, to which it is secured by a pin or rivet, and preferably has also formed thereon the socket R for the operating-handle S. Below the socket j' on the

casting J' is formed the upper half of a hollow screw-thread, terminating in a shoulder T , having an offset portion T' , with a shoulder t between T and T' . The casting J^2 has at its lower end a socket U , which fits on the rod H and is secured thereto by a pin or rivet. Above the socket U the casting J^2 has formed therein the lower half of a hollow screw-thread, terminating in a shoulder V , having an offset portion V' and a shoulder v between V and V' . If preferred, the handle-socket may be formed on the lower casting.

In assembling the castings J' and J^2 they are slipped onto the rod H and are brought together in such position that the shoulders T and V will be in contact, the offsets T' and V' being also in contact, the proper position of the parts of the screw-thread being determined by the contact of the small shoulders t and v . When in position, the castings J' and J^2 are secured to the rod H by pins or rivets, as shown. When mounted together, they form a cam-screw.

The upper portion of the bracket A is preferably recessed, as shown at A' , to receive the operating-handle when turned to bring the plunger down on the projection P' , and the bracket has near its upper end on the side opposite the recess A' a lug A^2 , on which the socket R rests when the handle is in its upper position.

The plunger I may be secured to the lower end of rod H in any convenient manner, as by a screw-thread.

In operation the handle S may be given nearly a full rotation by reason of the recess A' giving a long travel to the plunger, permitting it to be drawn upward a sufficient distance to allow of the half of a lemon or even a whole one to be readily placed on the projection P' . The screw J being of considerable strength the lemon or other fruit may be readily squeezed with sufficient force to completely express its juice, which passes down

through the opening u' into the glass or other receptacle, while the seeds, skin, and pulp are retained by the cup P , from which, the cup being removable, they may readily be thrown out.

Having thus described my invention, what I claim, and desire to secure by Letters Patent, is—

1. In a lemon-squeezer, the combination of a bracket, an arm secured to the bracket, provided with means for supporting the article to be squeezed, arms carried by the bracket, a rod carrying a plunger, mounted to rotate and to move vertically in said arms, and means for depressing the plunger comprising a screw secured to the rod, means for rotating the screw, and means carried by the bracket engaging the screw, said screw consisting of an upper and a lower casting, the upper casting being provided with a socket, to receive the plunger-rod and with a socket for the operating-handle and having formed thereon the upper edge of the screw, and the lower casting being provided with a socket to receive the plunger-rod and having formed thereon the lower edge of the screw; substantially as described.

2. In a lemon-squeezer, the combination of a bracket, an arm secured to the bracket provided with means for supporting the article to be squeezed, a rod carrying a plunger mounted in the bracket and provided with a screw, means on the bracket engaging the screw, means for operating the screw, and a lug carried by the bracket in position to sustain the handle in its raised position; substantially as described.

In testimony whereof I affix my signature in presence of two witnesses.

JOSEPH M. RIBERT.
